UNITED STATES PATENT OFFICE.

JOHN T. SCHEUERELL, OF MILWAUKEE, WISCONSIN, ASSIGNOR TO RALPH A. SMELSER,
OF MILWAUKEE, WISCONSIN

HAND GRIP FOR UNDERTAKERS.

Application filed September 25, 1924. Serial No. 739,773.

To all whom it may concern:

Be it known that I, JOHN T. SCHEUERELL, a citizen of the United States, and resident of Milwaukee, in the county of Milwaukee and State of Wisconsin, have invented certain new and useful Improvements in Hand Grips for Undertakers; and I do hereby declare that the following is a full, clear, and exact description thereof.

10 This invention relates to hand grips or suit cases for undertakers. Objects of this invention are to provide a hand grip which may be easily employed to transport a small body such as that of a 15 child, which is most readily adjustable to accommodate varying lengths of bodies, which is provided with an adjustable handle so that the handle may be positioned approximately over the center of gravity of the 20 body and will thus facilitate the carrying thereof.

Further objects are to provide an adjustable hand grip which may be most easily changed from one length to a different 25 length, which is provided with securing means for automatically locking the device in the desired position of adjustment, which is provided with interengaging top and bottom sections adapted to completely seal the 30 compartment, and which is so constructed that the top and bottom are together elongated and the composite top is adapted to open upwardly as a whole in a simple and effective manner.

35 Further objects are to provide a hand grip for an undertaker which is of attractive appearance, which may be contracted to a compact formation, and which is readily handled.

40 An embodiment of the invention is shown in the accompanying drawings, in which:

Figure 1 is a longitudinal sectional view through the device showing it in extended position, such view corresponding to a section on the line 1—1 of Figure 3.

Figure 2 is a rear side view of the device showing it contracted and closed.

Figure 3 is a transverse sectional view on the line 3—3 of Figure 2.

50 Figure 4 is a fragmentary detail of a portion of the non-extensible top showing a small portion of the extensible top as it appears when positioned over the non-extensible top.

Figure 5 is a detail of a portion of the 55 stationary bottom showing a fragment of the movable or extensible bottom.

Figure 6 is an enlarged detail of the latching means.

The device comprises a main portion 60 consisting of a bottom 1, an end 2 and a hingedly mounted top 3. This bottom is provided with an inwardly deflected metal member 4 which is secured by means of a plurality of screws or similar members 5 to the bottom portion. The upper part of this member 4 is overturned, as indicated at 6 (see Figure 3) to provide a channel.

The movable bottom portion or extensible 70 portion consists of a channel-like member 7 which is bent to conform to the portion 4, as may be seen from Figure 3 and whose upper deflecting edge 8 fits within the overturned channel like portion 6 of the member 4. The bottom of this extensible member or slid- 75 able portion rests upon the bottom 1 of the main member, as may be seen from Figure 1. Thus the extensible bottom may be drawn outwardly from the main bottom 1 to provide the necessary elongation to fit the 80 particular body carried within the grip. A spring fastener consisting of a leaf spring 9 (see Figures 1 and 6) is riveted, as indicated at 10, to the movable portion 7. This spring is provided with a manipulating end 11 and with a pin 12 which fits through an aperture 13 in the member 7 and is adapted to enter any one of the apertures 14 formed in the member 4 carried by the main portion 85 of the device, thus locking the extensible portion 7 in any desired position of adjustment. The end of the member 7 is finished by means of an end plate 15 corresponding to the end 2 of the main device, as may be 90 seen from Figures 1 and 2.

The top of the movable portion consists 95 of a channel like member having an upper portion 16 provided with a downwardly extending end 17 and downwardly extending lateral flanges 18. These flanges 18 fit in 100 channel strips 19 secured to the top 3 of the main device and are adapted to slide inwardly and outwardly, as may be seen from reference to Figures 1 and 3.

The handle consists of a hand grip portion 20 provided with snap fasteners 21 and 105 22 adapted to engage a central ring carrying bracket 23 and either of two outer brackets

24 or 25. For example when the device is in its extended position, as shown in Figure 1, the handle is secured to the brackets 23 and 24. When in its contracted position, as shown in Figures 3 and 4, the handle is secured to the brackets 23 and 25. This is readily secured by means of the snap fasteners 21 and 22 carried by the ends of the device. Obviously, the brackets may be slideable if desired, and may be slid to any suitable position although the present form is considered one of the simple and effective forms of positioning the handle approximately over the center of gravity of the loaded hand grip.

10 It is to be noted that the top of the main portion is hingedly joined to the lower portion, as indicated at 26, and is provided with any suitable form of lock 27 on its other side, as may be seen from Figure 3.

15 In using the device, assuming it is in its extended position, the torso or main body portion of the corpse is positioned within the main body portion 1 and the legs project into the extended portion, thus positioning the major portion of the weight directly beneath the handle.

20 It is to be understood that although the hand grip has been described as extensible in one direction only, obviously it may be made extensible from either or both ends in an obvious manner.

25 It will be seen, therefore, that a hand grip for undertakers has been provided which is eminently suited for the use of undertakers, which may be readily adapted to carry corpses of children from hospitals, scenes of accidents and other places, which may be readily transported and is of simple and 30 strong construction and of attractive appearance.

35 Although the invention has been described in considerable detail, it is to be understood that the invention may be variously embodied and is, therefore, to be limited only as 40 claimed.

I claim:

1. A hand grip for undertakers comprising a main body portion, a top hinged thereto, a handle secured to the top, and an extensible portion having a bottom part telescopically secured in the main body portion and having a top telescopically secured in the top of the main portion. 50

2. A hand grip for undertakers comprising a main body portion, a top hinged thereto, a handle secured to the top, said handle being adjustable longitudinally of said top and adapted to occupy any one of several positions, and an extensible portion 60 having a bottom part telescopically secured in the main body portion and having a top telescopically secured in the top of the main portion. 55

3. A hand grip comprising a main body 65 portion, a top hinged thereto, an extensible body portion slidably carried by the main body portion, guides carried by the main body portion and slidably receiving the extensible body portion, an extensible top portion 70 slidably carried by the top of the main portion, and guides carried by the top of the main portion and slidably holding the lower edge of the extensible top portion. 75

4. A hand grip comprising a main body 80 portion, a top hinged thereto, an extensible body portion slidably carried by the main body portion, guides carried by the main body portion and slidably receiving the extensible body portion, an extensible top portion 85 slidably carried by the top of the main portion, guides carried by the top of the main portion and slidably holding the lower edge of the extensible top portion, and a latch for detachably locking said extensible body portion to said main body portion. 90

In testimony that I claim the foregoing I have hereunto set my hand at Milwaukee, in the county of Milwaukee and State of Wisconsin.

JOHN T. SCHEUERELL.
